MASSAGING UNIT

Akihiko Teranishi, 8 3-chome, Yamawakimachi,
Showaku, Nagoya, Japan

Filed Jan. 6, 1966, Ser. No. 499

Term of patent 14 years

(Cl. D83—1)

FIG. 1 is a front elevation of a massaging unit showing my new design;

FIG. 2 is a top plan view of FIG. 1;

FIG. 3 is a bottom plan view of FIG. 1;

FIG. 4 is an elevation as seen from the rear of FIG. 1;

FIGS. 5 and 6 are side views taken from the right and left sides of FIG. 1, respectively.

The dominant features of my design reside in the portions shown in full lines.

I claim:

The ornamental design for a massaging unit, as shown and described.
